UNITED STATES PATENT OFFICE.

EWALD T. REICH, OF CHICAGO, ILLINOIS.

LUGGAGE CARRIER AND TABLE.

Application filed September 22, 1921. Serial No. 502,459.

To all whom it may concern:

Be it known that I, EWALD T. REICH, a citizen of the United States, residing at 3079 Ellridge Avenue, Chicago, in the county of Cook and State of Illinois, have invented a new and useful Improvement in Luggage Carriers and Tables, of which the following is a specification.

This invention relates to a combined 10 luggage carrier and table and is fully described in the following specification and shown in the accompanying drawings, in which:

Fig. 1 is a front elevation of the device 15 when used as a carrier;

Fig. 2 is an end elevation of the same; and

Fig. 3 is a partial end elevation showing the device used as a table.

20 This device consists of two spaced brackets each having a C-clamp 10 and a threaded locking screw 11 by means of which it is secured to the running board 12 of an automobile. A hollow tube 13 is secured to each clamp, the upper end of the tube being connected to the clamp by means of a brace 14.

25 A horizontal arm 15 is secured to a pin 16 which is hingedly mounted in the tube 13, the outer end of the arm 15 being supported by means of a brace 17 which is hingedly mounted upon the pipe 13.

30 Transverse slots 13^a are formed in the upper end of the tube 13. The arm 15 and the brace 17 are movable up and down on the tube 13. In the position shown in Fig. 1 the arms remain in a raised position on top of the tube 13 while in the position shown in Fig. 3 the arm 15 drops down into 35 the slot 13^a thereby preventing it from turning.

40 The flat member consisting of vertical and horizontal elements 18 and 19 secured together by means of hinges 20 forms the side of the luggage carrier as shown in Figs.

45 1 and 2 and is secured to the arms 15 by means of a bolt 21 and wing-nut 22. The bolt 21 passes through the member 18 and the arms 15, securing all three together by 50 means of the wing-nut 22. A series of holes 23 is provided in each of the arms 15 to accommodate various lengths of elements 18.

55 When it is desired to use the carrier as a table, the wing-nut 22 and bolt 21 are removed and the arms 15 swung outwardly

away from the car and at right angles to the position shown in Fig. 1 and into the position shown in Fig. 3, when the arm 15 will drop into the slot 13^a and lock them 60 against rotary movement. The screw 11 in one of the brackets is then loosened and the brackets moved a short distance towards the other and the screw 11 again tightened so as to clamp it in that position. The elements 18 and 19 are then moved to the position shown in Fig. 3 where they form the 65 top of the table.

When it is again desired to use this as a luggage carrier the table top is removed, 70 the bracket is moved back to the first position and the parts reassembled as shown in Fig. 1.

75 While I have shown and described certain embodiments of my invention, it is to be understood that it is capable of many modifications. Changes, therefore, in the construction and arrangement may be made without departing from the spirit and scope 80 of the invention as disclosed in the appended claims, in which it is my intention to claim all novelty inherent in my invention as broadly as possible in view of the prior art.

85 What I claim as new and desire to secure by Letters Patent is:

1. A combined luggage carrier and table comprising two brackets adapted to be secured to the running board of an automobile, an arm hingedly secured to each 90 bracket and movable to a first position parallel to the edge of the running board and to a second position substantially at an angle to the first position and a flat member adapted to lie across said arms in the 95 second position to form a table.

2. A combined luggage carrier and table comprising two brackets adapted to be secured to the running board of an automobile, an arm hingedly secured to each bracket 100 and movable to a first position parallel to the edge of the running board and to a second position substantially at an angle to the first position and a flat member 105 adapted to lie across said arms in the second position to form a table, said member being secured to said arms in the first position to form the side of a luggage carrier.

3. A combined luggage carrier and table comprising two brackets adapted to be secured to the running board of an automobile, an arm hingedly secured to each 110

bracket and movable to a first position parallel to the edge of the running board and to a second position substantially at an angle to the first position and a flat member adapted to lie across said arms in the second position to form a table, said member being composed of two flat elements hinged together, one of which is secured to said arms in the first position to form the side of a luggage carrier.

4. A combined luggage carrier and table comprising two brackets adapted to be secured to the running board of an automobile, an arm hingedly secured to each bracket and movable to a first position parallel to the edge of the running board and to a second position substantially at an angle to the first position, a flat member adapted to lie across said arms in the second

position to form a table, means for securing said arms in the first position and means for securing the arms in the second position.

5. A combined luggage carrier and table comprising two brackets adapted to be secured to the running board of an automobile, an arm hingedly secured to each bracket and movable to a first position parallel to the edge of the running board and to a second position substantially at an angle to the first position, a flat member adapted to lie across said arms in the second position to form a table, means for securing said arms to said member in the first position and means for securing the arms in the second position.

EWALD T. REICH.
